UNITED STATES PATENT OFFICE.

JAMES M. ROBERTS, OF MARION, KENTUCKY.

COMBINATION-LOCK.

1,224,569.

Specification of Letters Patent.

Patented May 1, 1917.

Application filed December 27, 1916. Serial No. 139,986.

To all whom it may concern:

Be it known that I, JAMES M. ROBERTS, citizen of the United States, residing at Marion, in the county of Crittenden and 5 State of Kentucky, have invented certain new and useful Improvements in Combination-Locks; and I do hereby declare the following to be a full, clear, and exact description of the invention, such as will enable 10 others skilled in the art to which it appertains to make and use the same.

This invention relates to a lock and has for one of its objects, the provision of a casing having a shackle adapted to be engaged and held by means located within the casing to prevent the shackle from being withdrawn from the casing or moved into an unlocked position.

Another object of this invention is to provide a combination means located within the casing and adapted to engage the ends of the shackle and prevent the same from moving into an unlocked position until the combination has been properly manipulated.

25 A further object of this invention is to provide a locking shaft having lugs thereon, which are received between U-shaped members having slots which are adapted to receive the lugs for permitting the shaft to rotate for freeing the shackle.

A further object of this invention is to provide means connected to the U-shaped members and extending exteriorly of the casing for moving the U-shaped members toward and from the shaft for permitting the lugs to turn in the slots for freeing the shaft.

A still further object of this invention is the provision of a combination lock of the above stated character, which shall be simple, durable and efficient, and which may be manufactured and sold at a comparatively low cost.

With these and other objects in view as will become more apparent as the description proceeds, the invention consists of certain novel features of construction, combination and arrangement of parts as will be hereinafter more fully described and claimed. For a complete understanding of my invention, reference is to be had to the following description and accompanying drawings, in which:

Figure 1 is a front elevation of a combination lock constructed in accordance with my invention;

Fig. 2 is a similar view partly in section having the cover removed,

Fig. 3 is a transverse sectional view illustrating means for holding the locking bar against rotation.

Fig. 4 is a detail perspective view of one of the U-shaped members.

Fig. 5 is a plan view of the locking bar,

Fig. 6 is a detail perspective view of the shackle,

Fig. 7 is an edge elevation illustrating means located upon the exterior of the casing for operating the combination of the lock.

Referring in detail to the drawing, the numeral 1 indicates a substantially rectangular casing having a removable cover 2 secured thereon by screws 3 or like fasteners. The top wall of the casing 1 is provided with openings 4 adjacent each end of the casing to receive the arm portions 5 and 6 of a substantially U-shaped shackle 7. The arm portion 5 of the shackle 7 has a reduced cylindrical portion 8 which is provided with a notch 9 and a lug 10. The arm portion 6 of the shackle 7 is provided with a reduced cylindrical portion 11 having a notch 12. Formed on the end of the reduced cylindrical portion 11 is a flat extension 13 having oppositely disposed lugs 14.

The end walls of the casing are provided with slots 15 for receiving a locking shaft 16, which has notches 17 and 18 formed adjacent each end for permitting the ends of the arm portions of the shackle 7 to pass under the locking shaft 16. Formed upon one end of the locking shaft 16 is a knob 19 for rotating the locking shaft 16 within the casing 1 and for causing the notches 17 and 18 to move out of an engagement with the ends of the shackle and permitting the portions 20 opposite to the notches 17 and 18 to enter the notches 9 and 12 of the arms 5 and 6 of the shackle, thereby preventing the shackle from being withdrawn from the casing.

Guides 21 are formed within the casing and have slidably mounted therein, substantially U-shaped members 22, which have their arm portions disposed upon each side of the locking shaft 16, as illustrated in Fig. 2. The arm portions of the substantially U-shaped members 22 are provided with oppositely disposed elongated slots 23. Formed upon the locking shaft 16 are pairs 110

of oppositely disposed lugs 24 which are adapted to engage the inner faces of the arm portions of the substantially U-shaped members 22 and prevents the locking shaft 5 from rotating within the casing by the knob 19. Operating rods 25 are journaled in the bottom wall of the casing 1 and have formed upon their outer ends, knobs 26 for rotating the operating rods. The operating rods 25 10 extend into the guides 21 and are threaded into an engagement with the web portion of the substantially U-shaped members 22 for sliding the substantially U-shaped members 22 in the guides 21 for permitting the slots 23 to become so positioned that the lugs 24 may pass therein when the locking shaft 16 is turned by the knob 19 thus freeing the shackle 7 from a locked position. The arm portion 6 of the shackle 7 is prevented from entirely withdrawing from the casing by the oppositely disposed lugs 14 15 engaging the underface of the top wall. The extension 13 formed upon the arm portion 6 of the shackle 7 adds a greater length 20 to said arm portion than the arm portion 5 and when the oppositely disposed lugs 14 engage the underface of the top plate of the casing, the arm 5 will be free from the casing, permitting the shackle to be removed 25 from a staple or other device which it is locking.

The knobs 26 may have formed thereon indicators as illustrated in Fig. 7 adapted to coöperate with combination figures located upon the bottom wall of the casing whereby a person when desiring to unlock the shackle 7 can tell by the indicating hand moving upon the graduations the number of times it is necessary to rotate the operating rod 25 before the slots 23 in the substantially U-shaped members 22 are so positioned as to permit the lugs 24 to turn or extend therein.

From the foregoing description taken in connection with the accompanying drawing, it will be noted that applicant has provided a lock which may be readily operated without the use of a key and which consists of compact and convenient arrangement of 45 parts, which may be readily manipulated so that the shackle of the lock can be freed.

While I have shown and described the preferred embodiment of my invention, it will be understood that minor changes in 50 construction, combination and arrangement of parts may be made without departing from the spirit and scope of the invention as claimed.

Having thus described my invention, what 55 I claim is:

1. A lock comprising a casing, a substantially U-shaped shackle having its ends dis-

posed within the casing and notched, a shaft journaled in the casing and having notches for coöperating with the notches in the shackle to permit the shackle to slide freely within the casing, a knob formed on the shaft and exteriorly of the casing for rotating the shaft to move said shaft into the notches of the shackle to lock said shackle against withdrawal from the casing, means engaging the shaft to lock it against rotation, and means connected with the last mentioned means and extending exteriorly of the casing for moving said means to free the shaft.

2. A lock comprising a casing, a substantially U-shaped shackle having its ends extending within the casing and notched, a shaft journaled within the casing and having notches for coöperating with the notches in the shackle to permit the shackle to slide freely in the casing, means for rotating the shaft to move said shaft into the notches of the shackle to lock said shackle against withdrawal from the casing, oppositely disposed lugs formed on the shaft, substantially U-shaped members located within said casing and receiving the shaft between its arm portions, said U-shaped members having elongated slots in the arm portions, means for moving the substantially U-shaped members to position the slots for receiving the lugs for permitting the shaft to be rotated.

3. A lock comprising a casing, a substantially U-shaped shackle having its ends disposed within the casing and notched, a shaft journaled in the casing and having notches therein for coöperating with the notches in the shackle to permit the shackle to slide within the casing, means for rotating the shaft to move said shaft into the notches of the shackle, guides formed within the casing, substantially U-shaped members slideable in the guides and receiving the locking shaft between their arm portions, said U-shaped members having elongated slots in the arm portions thereof, oppositely disposed lugs formed on the shaft and located between the arm portions of the substantially U-shaped members, and operating rods journaled in the casing and threaded to the substantially U-shaped members for moving said U-shaped members to position the slots so as to permit the lugs to enter them for permitting the shaft to be rotated.

In testimony whereof I affix my signature in presence of two witnesses.

JAMES M. ROBERTS.
